CURTAIN FIXTURE

Filed July 22, 1929

Inventor:

Harry D. Severson,

By Cromwell, Grist & Warden

UNITED STATES PATENT OFFICE

HARRY D. SEVISON, OF ELKHART, INDIANA, ASSIGNOR TO THE ADLAKE COMPANY, OF CHICAGO, ILLINOIS, A CORPORATION OF ILLINOIS

CURTAIN FIXTURE

Application filed July 22, 1929. Serial No. 379,910.

This invention has to do with curtain fixtures of the type in which a pair of laterally spring-pressed holding members are carried by the lower end of an upwardly spring-drawn car window curtain in frictional engagement with guides at the sides of the curtain.

In curtain fixtures of the type described, the holding members are retracted, when the curtain is raised or lowered, by a pair of centrally located finger pieces which are connected with the holding members. The finger pieces, however, usually rattle a little under the constant vibration, jars, impacts and shocks incident to railway service, which noise is particularly objectionable in sleeping cars and becomes more and more pronounced as certain of the fixture parts loosen up or become worn in service.

The purpose of this invention is to provide simple, inexpensive, durable and efficient means for preventing the finger pieces of a curtain fixture from rattling.

While the foregoing statement is indicative in a general way of the nature of the invention, other objects and advantages will be apparent to those skilled in the art upon a full understanding of the construction, arrangement and operation of the novel silencing device.

One form of the invention is presented herein for the purpose of exemplification, but it will of course be understood that the invention is susceptible of embodiment in other structurally modified forms coming equally within the scope of the appended claims.

In the accompanying drawing:

Fig. 1 is a front view of a curtain fixture equipped with the silencing device of the invention;

Fig. 2 is a longitudinal section through one of the duplicate ends of the fixture;

Fig. 3 is a transverse section, taken on the line 3—3 of Fig. 1; and

Fig. 4 is an interior view, showing the manner in which the double spring clip, which is secured to the inner face of the center plate, embraces the finger pieces, one of

the finger pieces being removed for clearness of illustration.

The curtain fixture shown in the drawing is structurally the same as that shown in Whitmore application Serial No. 330,171, 55 and therefore need not be described in detail. Briefly, it consists of a tube 10 which is adapted to be encased in the lower end of an upwardly spring-drawn window curtain. The tube carries two outwardly spring-pressed heads 11 which are adapted to ride up and down in two grooved guides 12 attached to the opposite sides of the associated window frame. The tube also carries two outwardly spring-pressed rods 13 which are connected at their inner ends to two finger pieces 14 and are connected at their outer ends to two cams 15. The finger pieces 14 are adapted to retract the cams 15 away from the bottoms of the grooves in the guides, 60 while the cams 15 are adapted to wedge frictionally against the guides to prevent vertical movement of the fixture.

The finger pieces 14 are provided with flattened finger-engaging portions 16 on the outside of the tube, and with elongated interiorly threaded portions 17 within the tube at right angles to the portions 16, which interiorly threaded portions receive the inner threaded ends of the rods 13. A plate 18 is secured by a screw 19 to the tube over an opening in one side of the center of the same, and is provided with two axially elongated slots 20 through which the finger pieces 14 extend.

A pair of thin spring metal plates 21 having overlapping ear portions 22 are secured against the inner face of the plate 18 by an eyelet 23 which extends about the edge of the screw aperture in the same. The spring plates 21 are provided with inturned flanges 24, in opposed pairs, which flanges press resiliently against opposite flattened surfaces 25 on the rod-engaging portions 16 of the finger pieces, whereby to hold the finger pieces snugly against any sidewise movement. The normal spacing of the flanges 24, with the finger pieces removed, is slightly less than the distance between the flattened surfaces 25 on the finger pieces, with the result

that, when the finger pieces are inserted, the flanges bear resiliently against the sides of the same with a certain amount of pressure.

The provision of the silencing device does not add materially to the cost of the fixture, but does greatly enhance the value of the same by reason of the way in which it effectively eliminates the noise heretofore caused by the sidewise movement of the finger pieces. While the silencing device has been illustrated and described herein in connection with one particular form of curtain fixture, it will of course be appreciated that it is equally applicable to various other forms of curtain fixtures having finger pieces for use in operating the same.

I claim:

1. In a curtain fixture, means for holding a curtain against upward movement, means for retracting the holding means, and means acting against the retracting means to prevent the same from rattling.
2. In a curtain fixture, normally extended holding members, finger pieces for retracting the same, and means acting against the finger pieces to prevent the same from rattling while the holding members are extended.
3. In a curtain fixture, normally extended holding members, finger pieces for retracting the same, spring means bearing resiliently against the finger pieces to prevent the same from rattling while the holding members are extended.
4. In a curtain fixture, a tube, upwardly spring-pressed holding members at the ends of the tube, finger pieces projecting laterally from one side of the tube at the center of the same for retracting the holding members, and spring clips compressibly embracing the portions of the finger pieces within the tube to prevent the finger pieces from rattling.
5. In a curtain fixture, a tube, outwardly spring-pressed holding members at the ends of the tube, a plate attached to the tube over an opening in the center of one side of the same, finger pieces connected within the tube to the holding members and projecting laterally through elongated slots in the plate for retracting the holding members, and spring clips carried by the plate within the tube and compressibly embracing the portions of the finger pieces within the tube to prevent the finger pieces from rattling.

In witness whereof I have hereunto subscribed my name.

HARRY D. SEVISON.
